CIGARETTE DISPENSER

Mark Anthony Bucci and Anthony Bucci, Jr.,
Hoboken, N.J.

Application December 4, 1957, Serial No. 700,598

3 Claims. (Cl. 221—190)

This invention relates to a cigarette dispenser, so designed that on elevation of a slotted upper portion of the dispenser, and subsequent depression of the same to a normal position, a single cigarette will appear in the slot, in convenient position for removal by a user.

It is known to provide dispensers for objects, such as matches, which in a broad sense, operate on the same principle as the present invention. The main object of the present invention is to provide an improved construction for a dispenser of this type, particularly designed to facilitate manufacture of the device from a very low cost material, such as cardboard.

Another object of importance is to provide a dispenser of the character stated, formed of cardboard or other readily workable and easily cut stock, which will be designed with means interengaging between the upper and lower portions, to hold the upper portion against complete separation from the lower portion.

Another object is to provide a construction for a dispenser of the character stated wherein the interengaging means acts only when the upper portion is moved to a raised position, predetermined as the correct position for locating a cigarette properly for dispensing.

Yet another object, in the above-mentioned modification of the invention, is to provide a cigarette-supporting center partition that will not only be formed of a low-cost material, but will be transversely compressible by a user in a manner to deliberately disengage the upper and lower portions from one another, whereby to permit the intentional full separation of the upper from the lower portion, in the event of malfunctioning of the device, or in the event one desires to change the cigarettes therein before all the cigarettes have been dispensed.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of the device with the cover portion raised.

Fig. 2 is a perspective view with the cover portion lowered to expose a dispensed cigarette.

Fig. 3 is an enlarged transverse sectional view substantially on line 3—3 of Fig. 2, the dotted lines showing the cover portion in raised position.

Fig. 4 is an exploded perspective view of the device in which portions have been shown in section.

Fig. 5 is a perspective view of a modified base portion, portions being shown in section.

Fig. 6 is a fragmentary sectional view on substantially the same cutting plane as Fig. 3, showing the modified construction of Fig. 5.

In the form of the invention shown in Figs. 1—4, there is illustrated a base generally designated 10, said base

2

including a base plate 11 of flat rectangular formation which, as shown in Fig. 4, may be coated over a substantial part of its area with adhesive 12, for permanently connecting to the base a rectangular, upwardly opening body portion generally designated at 14.

At this point, it should be noted that the entire device is formed of a cardboard material, and said cardboard could be covered with paper, or other ornamental covering, if desired. This is considered sufficiently obvious as not to require special illustration herein.

In any event, the cardboard would, of course, be fashioned from a suitable blank, and when the blank is cut and folded, there would be provided a box-like body portion 14 shown to particular advantage in Fig. 4. This includes side walls 18 and end walls 20, extending upwardly from the periphery of a flat bottom wall 16. The body portion, in other words, is merely a cardboard blank folded in the form of an upwardly opening, rectangular box.

Designated generally at 22 is a center partition extending vertically upwardly from bottom wall 16, with the upper end of the partition being disposed at a level slightly above the upper ends of the several walls (see Fig. 3). The partition 22 is also formed from a blank of cardboard material, folded upon itself to include closely spaced side walls 24, integral at their lower ends with inwardly directed, confronting flanges 26 adhesively secured to bottom wall 16.

At its top, the partition 22, which is of inverted U-shape in cross section, has a transversely depressed bight portion 30 providing a support ledge for a cigarette C to be dispensed.

It will be apparent that a cigarette moving into position upon the channeled or transversely depressed rest or ledge 30 will remain thereon by reason of the channeled formation of said ledge.

In any event, in a preferred embodiment, the partition has at its upper end projections 28 on the walls 24, said projections terminating, however, in closely spaced relation to the respective walls 20.

Designated generally at 32 is a cover portion of the dispenser, having a rectangular body 34 slidably telescoping in the body 14 of the base. Body 32 has side walls 36 slidably contacting the inner surfaces of walls 18, and end walls 36 slidably contacting the inner surfaces of walls 20, in the space between the walls 20 and the projections 28 of partition 22.

Inwardly directed, confronting flanges 38 are formed on the upper ends of walls 34, coated with adhesive for a purpose to be made apparent. Integral with the lower ends of walls 34 are confronting, inwardly projecting, wide flanges 39 terminating at their confronting edges in close proximity to the center partition 22 (see Fig. 3). Flanges 39 merge, at their partition-adjacent edges, into upwardly directed portions 41 which in turn merge, at their upper ends, into oppositely sloped walls 40 diverging in a direction upwardly from the portions 41. Walls 40, at their divergent, upper ends, are integral with attaching flanges 43 that are adhesively secured to the inner surfaces of the walls 34.

Designated at 42 is a top plate of the cover portion 32, having a slot 44 adapted to receive the upper end of the partition 22 (see Figs. 2 and 3) when the cover portion is lowered.

In use, a quantity of cigarettes is deposited within the dispenser, as opposite sides of the partition, within compartments 46 defined at said opposite sides of the partition, the bottom walls of said compartments being the sloped walls 40. By reason of this arrangement, the cigarettes tend to gravitate toward and into engagement with the opposite surfaces of the partitions. Therefore, when the cover portion is raised as in Fig. 1 and as in

dotted lines in Fig. 3, one cigarette will fall into the channel of the ledge 30. Then, lowering of the cover portion to the Fig. 2 position will locate said cigarette in exposed position, dispensed for a user. The dispensing action will continue each time the cover portion is raised and then lowered, until the quantity of cigarettes is exhausted.

A desirable characteristic of the invention resides in the fact that it can be formed entirely from cardboard or the like. The body of the cover portion 32, for example, can be formed of a blank of cardboard, integrally formed with extensions bendable to provide the flanges 39, portions 41, and sloped walls 40.

In the modified form shown in Figs. 5 and 6, the base 10 is identical in every respect to that of the first form. The cover portion 32a is identical to that of the first form, in respect to having a depending, rectangular body formed with walls 34a, 36, and in respect to having flanges 39a merging into portions 41a that in turn merge into upwardly divergent, sloped walls 40a. The only difference between the form shown in Fig. 5 and the form of cover portion shown in Figs. 1-4 resides in the fact that at the ends of the portions 41a, small slits 45 are formed, defining spring tongues 46. Since cardboard is used, there will be an inherent springability in the tongues, which even though relatively low, will be sufficient for its intended purposes.

The tongues 46 are bent inwardly as in Figs. 5 and 6, so that the confronting faces thereof converge in an upward direction.

Now, the tongues 46 are of a width only sufficient to permit them to move into the open spaces below the overhangs or projections of partition 22. Therefore, when the cover portion is positioned upon the base and is moved downwardly, tongues 46 will initially be sprung apart by the projections 28. When the tongues move to a position below the projections, however, the inherent springability of the tongues will be permitted to assert itself and the tongues will now move into the Fig. 6 position, in which positions they are disposed under the overhangs, whereby to locate the overhangs in the path of movement of the tongues in the event the cover portion is moved upwardly to the Fig. 1 position.

Therefore, the tongues 46 will engage the overhangs 28 to limit movement of the cover portion beyond the raised position shown in Fig. 1 and in dotted lines in Fig. 3, which position is determined to be proper for dispensing the cigarettes, that is, for locating the cigarette upon the ledge 30. Complete separation of the cover and base portions will be prevented, however, in these circumstances.

If it is desired to deliberately separate the cover portion and base portion, as for example when it is desired to remove the cigarettes that are already in the device and replace them with fresh cigarettes, before all cigarettes have been dispensed, one merely exerts a squeezing pressure against the partition, with eyebrow tweezers or the like inserted through slot 44. Now, when the dispenser is raised with the partition squeezed, the distance between the walls 24, and hence between the projections 28, will be reduced sufficiently to permit the tongues 46 to move past the projections, thereby allowing full separation of the cover and base portions.

This construction, thus, will normally prevent full separation of the cover and base portions, but will allow said separation if needed.

It is to be understood that this cigarette dispenser may be made of any suitable sheet material, such as plastic, metal, etc.

While we have illustrated and described the preferred embodiments of our invention, it is to be understood that we do not limit ourselves to the precise constructions herein disclosed and that various changes and modifications may be made within the scope of the invention as defined in the appended claims.

Having thus described our invention, what we claim as new, and desire to secure by United States Letters Patent is:

1. A cigarette dispenser comprising a base including an upwardly opening body, a partition extending upwardly within the body and formed at its upper end with a support ledge for a cigarette to be dispensed, a cover portion slidably telescoped in the open upper end of the body, said cover portion including a top plate having a slot and a rectangular body portion slidably telescoped in said body, said body portion having a lower part formed with sloped, upwardly divergent side walls disposed at opposite sides of and slidably contacting said partition to direct toward the partition cigarettes carried on the sloped walls, whereby a cigarette will be moved onto said ledge on raising of the cover portion, and will be exposed for removal by a user when the cover portion is lowered, said slot being slightly wider than the partition, said sloped walls terminating at opposite ends of the body portion, the partition being formed with overhangs at opposite ends thereof closely spaced from the adjacent walls of said body of the base to provide spaces adapted to be entered by corresponding walls of the body portion, the partitions below the overhangs being spaced a greater distance from said adjacent walls of the body, said cover portion being formed at opposite ends thereof with pairs of upwardly convergent spring tongues, said tongues being tensioned to extend under the overhangs to limit movement of the cover portion upwardly from the base.

2. A cigarette dispenser comprising a base including an upwardly opening body, a partition extending upwardly within the body and formed at its upper end with a support ledge for a cigarette to be dispensed, a cover portion slidably telescoped in the open upper end of the body, said cover portion including a top plate having a slot and a rectangular body portion slidably telescoped in said body, said body portion having a lower part formed with sloped, upwardly divergent side walls disposed at opposite sides of and slidably contacting said partition to direct toward the partition cigarettes carried on the sloped walls, whereby a cigarette will be moved onto said ledge on raising of the cover portion, and will be exposed for removal by a user when the cover portion is lowered, said slot being slightly wider than the partition, said sloped walls terminating at opposite ends of the body portion, the partition being formed with overhangs at opposite ends thereof closely spaced from the adjacent walls of said body of the base to provide spaces adapted to be entered by corresponding walls of the body portion, the partitions below the overhangs being spaced a greater distance from said adjacent walls of the body, said cover portion being formed at opposite ends thereof with pairs of upwardly convergent spring tongues, said tongues being tensioned to extend under the overhangs to limit movement of the cover portion upwardly from the base, said base and cover portion being formed wholly of cardboard material, the tongues being struck out of said cardboard material.

3. A cigarette dispenser comprising a base including an upwardly opening body, a partition extending upwardly within the body and formed at its upper end with a support ledge for a cigarette to be dispensed, a cover portion slidably telescoped in the open upper end of the body, said cover portion including a top plate having a slot and a rectangular body portion slidably telescoped in said body, said body portion having a lower part formed with sloped, upwardly divergent side walls disposed at opposite sides of and slidably contacting said partition to direct toward the partition cigarettes carried on the sloped walls, whereby a cigarette will be moved onto said ledge on raising of the cover portion, and will be exposed for removal by a user when the cover portion is lowered, said slot being slightly wider than the partition, said sloped walls terminating at opposite ends of

the body portion, the partition being formed with overhangs at opposite ends thereof closely spaced from the adjacent walls of said body of the base to provide spaces adapted to be entered by corresponding walls of the body portion, the partitions below the overhangs being spaced a greater distance from said adjacent walls of the body, said cover portion being formed at opposite ends thereof with pairs of upwardly convergent spring tongues, said tongues being tensioned to extend under the overhangs to limit movement of the cover portion upwardly from the 10 base, said base and cover portion being formed wholly of cardboard material, the tongues being struck out of said cardboard material, the partition being of approximately inverted U-shape in cross section and being compressi-

ble manually to dispose the overhangs out of the path of the tongues, whereby to permit intentional separation of the cover portion and base.
